UNITED STATES PATENT OFFICE.

GEORGE H. HOWLAND AND TIMOTHY F. OLMSTED, OF NORTHVILLE,
NEW YORK.

DESIGN FOR A FRICTION-LOOP FOR FIRE-ESCAPES.

SPECIFICATION forming part of Design No. 26,071, dated September 22, 1896.

Application filed August 7, 1896. Serial No. 602,088. Term of patent 14 years.

To all whom it may concern:

Be it known that we, GEORGE H. HOWLAND and TIMOTHY F. OLMSTED, citizens of the United States, residing at Northville, in the 5 county of Fulton and State of New York, have invented and produced a new and original Design for Friction-Loops for Fire-Escapes; and we do hereby declare the following to be a full, clear, and exact description of the same, 10 reference being had to the accompanying drawing, forming a part thereof.

The figure in the accompanying drawing represents our design for friction-loops for fire-escapes.

15 The leading feature of our design consists of an approximately oblong frame or loop having a straight bar extending diametrically through the same parallel with its long sides, with eyes located on the loop at each 20 end of said bar, and other eyes at the middles of the long sides of the loop.

A in the drawing represents an approximately oblong frame or loop, preferably having rounded corners.

25 *a* represents a straight bar or rod which

extends diametrically through the loop from end to end and parallel with the long sides, and adapted to have a lowering-rope twisted about it.

a' a' represent eyes which are located on 30 the frame or loop, at the top and bottom of the same, in line with the central bar or rod, through which the said lowering - rope is adapted to pass, and *a²a²* represent eyes which are located on the frame or loop at the long 35 sides thereof, which are adapted to receive the ends of a supporting-rope which would be passed under the arms of a descending person.

What we claim is—

The design for a friction-loop for a fire-escape, substantially as herein described and shown.

In testimony whereof we hereunto affix our signatures in presence of two witnesses.

GEORGE H. HOWLAND.
TIMOTHY F. OLMSTED.
